UNITED STATES PATENT OFFICE.

WILLIAM WEIR, OF CATHCART, SCOTLAND.

STEAM-ENGINE AIR-PUMP.

No. 825,950.

Specification of Letters Patent.

Patented July 17, 1906.

Application filed September 28, 1905. Serial No. 280,492.

To all whom it may concern:

Be it known that I, WILLIAM WEIR, a subject of the King of the United Kingdom of Great Britain and Ireland, residing at Cathcart, Renfrewshire, Scotland, have invented certain new and useful Improvements in Steam-Engine Air-Pumps, of which the following is a specification.

My invention has for its object by a novel construction and combination of parts to improve the working of vertical air-pumps of the single-acting type when these are driven independently and directly by the piston-rods of steam-cylinders, to overcome the defects in working of this type of pump due to the unequal and unbalanced loads on the air-pump piston on its upward and downward stroke, and to diminish the height and generally secure compactness in the design of such air-pumps.

This invention is applicable to single vertical direct-acting air-pumps driven by steam-cylinders fitted with any type of actuating steam-valve.

According to my invention and as illustrated in vertical section in the accompanying drawing, which shows a single direct-acting air-pump fitted with my improvements, I arrange on the under side of the main steam-cylinder A a prolongation thereof A', but of less diameter, having its lower end open. In this smaller or differential cylinder A' works a trunk or plunger B, which is attached to the main cylinder-piston C and rod D. The top side *a* of the main steam-cylinder A is in communication with the steam and exhaust ports *e* of the steam-actuating valve E. The under side of the main steam-cylinder piston at *a'* is arranged to be always in communication with the steam-supply pipe, as by a branch F, so that the under side of the main piston C is always subject to the working steam-pressure.

The action of the pump when fitted with this improvement is as follows: On the upward or discharge stroke of the air-pump G the under side of the main piston C, less the area of the differential plunger B, is subject to the steam-pressure and is available for actuating the pump. On the downward stroke the upper side of the main piston C and the under side also, less the area of the differential trunk or plunger B, are subject to the steam-pressure. There is therefore only an area equal to that of the differential trunk or plunger B available for actuating

the pump, and the size of this differential plunger is accordingly arranged to permit the pump G to make its downward stroke at the speed desired.

For the purpose of securing greater compactness and decreasing the height of the pump the pump-cover—*i. e.*, the cover H of the pump-casing—is arranged and constructed to support the main and differential cylinder A' and to form a closed communicating chamber *h* between the open end of the differential cylinder and the portion of the air-pump above the discharge-valves J.

By this construction for an air-pump working with surface condensers any leakage of steam from the under side of the main cylinder A past the differential plunger B will be absorbed by the water which the pump is pumping during its passage from the air-pump G, and as this water is generally used for feeding boilers the arrangement will prevent any heat loss.

The movement of the steam-valve E, which may be the auxiliary valve of any well-known type of valve-gear, is secured by attaching to the air-pump bucket G' a supplementary rod K, passing through a gland L on the pump-cover H, working on a guide L', attached to the steam-cylinder A, and actuating through a cross-head M and levers N an attachment, such as the swivel-pin O, to the valve-spindle P, so as to move the steam-valve E synchronously with the movement of the air-pump bucket G'.

Having now described my invention, what I claim, and desire to secure by Letters Patent of the United States, is—

1. In a single-acting pump, the combination with a main steam-cylinder, of an auxiliary cylinder forming an extension of and of lesser diameter than the said main cylinder, and having an open lower end, a main piston or plunger fitting in said main cylinder, an auxiliary piston or plunger fitting in the said auxiliary cylinder, a pump-casing having a cover or upper extension H forming a chamber *h* separate from the pump-chamber and into which said pump-chamber discharges, said chamber *h* being open at its top and communicating with the chamber of the said open-ended auxiliary cylinder, and a pump plunger or piston operated from the said main and auxiliary pistons or plungers.

2. In a single-acting pump, the combination with a main steam-cylinder, of an auxiliary cylinder forming an extension of and of

lesser diameter than the said main cylinder, and having an open lower end, a main piston or plunger fitting in said main cylinder, an auxiliary piston or plunger fitting in the said auxiliary cylinder, a pump-casing having a cover or upper extension H forming a chamber h separate from the pump-chamber and into which said pump-chamber discharges, said chamber h being open at its top and communicating with the chamber of the said open-ended auxiliary cylinder, a pump plunger or piston operated from the said main and auxiliary pistons or plungers, and a steam-valve operated from said pump piston or plunger.

3. In a single-acting pump, the combination with a main steam-cylinder, of an auxiliary cylinder forming an extension of and of lesser diameter than the said main cylinder, and having an open lower end, a main piston or plunger fitting in said main cylinder, an auxiliary piston or plunger fitting in the said

auxiliary cylinder and partly covering the lower face of said main piston or plunger, a pump-casing having a cover or upper extension H forming a chamber h separate from the pump-chamber and into which said pump-chamber discharges, said chamber h being open at its top and communicating with the chamber of the said open-ended auxiliary cylinder, a pump plunger or piston operated from the said main and auxiliary pistons or plungers, a steam-valve operated from said pump piston or plunger, and means for admitting a continuous supply of boiler-steam to the lower face of said main piston or plunger.

In testimony whereof I have signed my name to this specification in the presence of two subscribing witnesses.

WILLIAM WEIR.
